NAIL SETTER

Arthur Prescott Barker, Lynn, Mass.

Application December 15, 1932, Serial No. 647,405

1 Claim. (Cl. 1-47)

This invention relates to combination nail sets and measuring gauges and is designed particularly for use in the application of weather strips and other fixtures, drapery rods, etc, where an exact locating of the weather strip or other fixture is essential and where difficulty is experienced in simultaneously holding and driving the nail and locating the fixture prior to the driving process.

10 It has for its purposes to provide a novel and efficient means of simplified and inexpensive construction for holding a nail prior to the driving thereof; to provide a convenient gauge by means of which the article or fixture to be installed may be accurately and uniformly positioned at a proper distance from a given point or working line; and to provide the various other advantages and results made evident from the following specification.

15 20 I accomplish the objects of my invention by providing a nail set of plurality parts, one part of which comprises the portion designed to be held in the hand while the tool is being used, and another part slideably mounted therein. 25 The first mentioned part is provided at one end with gauging means designed to facilitate the proper positioning of the weather strips or other fixtures to be applied with reference to a given working line or point. The gauging means may 30 be integral with the first mentioned part or constructed so as to be removable when its use is not desired, and may be replaced by other gauging means of any desired size when a different spacing is required.

35 Referring to the accompanying drawing which forms a part of this specification and in which similar letters of reference refer to similar parts throughout the various views, Figure 1 shows my assembled device with a part of the handle portion cut away to show the interior construction, and with the slideable portion therein mounted in extended position at which it is normally just prior its use. Figure 2 shows a view of the device at right angles to that shown 40 in Figure 1 with the slideable portion in contracted position as it is normally just after the tool has been used in driving or setting the nail. Figure 3 shows a side view of the handle portion. Figure 4 shows the driving end view of the 45 handle portion. Figure 5 shows the opposite end view of the handle portion. Figure 6 shows the details of the slideable portion. Figure 7 shows a lower end view of the slideable portion.

50 Referring again to the drawing, A shows the handle portion. B shows the slideable portion.

B² shows the cut away part of the member B. C shows the holding screw which projects through the handle member A, fits into the cut away portion B² and thus anchors the slideable member within the handle yet allows it sliding motion therein. B³ shows the nail end of the slideable member. D shows the gauge formation at the nail end of the handle portion. E shows the springs positioned within the nail end of the handle portion which functions to secure the nail when positioned within the nail end of said handle portion.

55 While I have illustrated and described a preferred construction for carrying my invention into effect, this is capable of variation or modification without departing from the spirit of the invention. I therefore do not wish to be limited to the exact details of construction herein set forth but desire to avail myself of such variations and modifications as come within the scope 60 of the appended claim.

Having thus described my invention, I claim as new and desire to secure by Letters Patent of the United States of America:—

65 A nail inserting implement comprising a tubular casing having therein bores of different diameters, the larger bore being located in the upper portion of the casing which is provided with a gripping surface on its outer face, a plunger mounted within said bores and having portions conformable thereto and slideable therein, means to retain the plunger within said casing, the lower portion of the casing having a downwardly tapered bevel extending to an end portion which is the same diameter as the casing 70 except for two flattened portions which form 75 gauges for projection between portions of the work to be nailed.

A. PRESCOTT BARKER.
